UNITED STATES PATENT OFFICE.

ALBRECHT VOGT, OF ROCHESTER, NEW YORK.

DESIGN FOR A MOLDING.

SPECIFICATION forming part of Design No. 15,032, dated May 27, 1884.

Application filed December 26, 1883. Term of patent 7 years.

To all whom it may concern:

Be it known that I, ALBRECHT VOGT, of Rochester, Monroe county, New York, have invented or produced a new and original Design for Moldings; and I do hereby declare that the following is a full, clear, and exact description of the same, reference being had to the accompanying drawings, in which—

Figure 1 is a face view of the molding.
10 Fig. 2 is a cross-section of the same.

My design relates to moldings for frames and other purposes, and is of that kind where the molding is covered with a braiding or plattting of thread.

15 The design consists of such a molding provided with diagonal or spiral lines of tufted work on the exterior, which relieves the monotony of a plain surface and presents a pleasing appearance to the eye.

20 In the drawings, A shows the molding. b shows a platted surface. c c are diagonal or

spiral lines of tufted work at regular distance apart, and which stand off from the surface. The braided or platted surface presents a fine background, while the spiral lines of tufted work break or diversify the plain surface and relieve the monotony. The whole forms a highly-ornamental appearance. 25

What I claim as new, and desire to secure by Letters Patent, is—

30 The design herein described, consisting of a molding having a platted or braided surface, and spiral lines of tufted work extending around the same at regular distances apart, as shown and described.

35 In witness whereof I have hereunto signed my name in the presence of two subscribing witnesses.

A. VOGT.

Witnesses:

R. F. OSGOOD,
WM. J. MCPHERSON.
